LAMP BULB HOLDER

Nathan G. Jagoda, 5920 Lockton Lane,
Mission, Kans. 66222

Filed June 9, 1969, Ser. No. 17,587

Term of patent 14 years

Int. Cl. D26—02, 06

U.S. Cl. D48—4

Fig. 1.

FIG. 1 is a front elevational view of the lamp bulb holder, the lamp and lamp bulbs being shown in broken lines for illustrative purposes only.

FIG. 2 is a side elevational view of the lamp bulb holder, the lamp bulb being shown in broken lines for illustrative purposes only.

FIG. 3 is a plan view of the lamp bulb holder.

I claim:

The ornamental design for a lamp bulb holder, as shown and described.
